CLAIM

The ornamental design for a security plate, as shown and described.

DESCRIPTION

FIG. 1 is a front perspective view of a security plate showing my new design.

FIG. 2 is a front view of the security plate shown in FIG. 1. FIG. 3 is a rear view of the security plate of FIG. 1.

FIG. 4 is a right side view of the security plate of FIG. 1.

FIG. 5 is a left side view of the security plate of FIG. 1. FIG. 6 is a top plan view of the security plate of FIG. 1; and, FIG. 7 is a bottom view of the security plate of FIG. 1.

The broken lines are included for the purpose of illustrating portions of the security plate that are not considered part of the claimed design.
